ALARM SYSTEM FOR HEAT EXCHANGE DEVICES

Herbert H. Rauh, Columbus, Ohio, assignor to
Ranco Incorporated, Columbus, Ohio, a corporation of Ohio

Application February 5, 1945, Serial No. 576,290

6 Claims. (Cl. 177—311)

1

The present invention relates to a control system for a heat exchange device such as a refrigerator. Heat exchange devices are usually automatically operated and at times are overloaded. Also, the automatic control mechanism may fail to operate.

One of the objects of the present invention is to provide a signal which will warn the user of the device of an abnormal condition of the device, such as, for example, an overloaded condition on the device or a failure of the automatic controlling mechanism.

In the event of an overload condition, the heat exchange can be continued, however the signal may be annoying and, therefore, it is a further object of the present invention to manually discontinue the signal, yet provide for conditioning the signal for recurrent operation in the event of another abnormal condition such as overloading the heat exchange device, or the failure of the automatic control.

A heat exchange device usually employs a current consuming element, such as an electric motor, and such element is usually intermittently energized to operate the exchange device. It is still another object of the present invention to concurrently recondition the signal for operation, if it had been previously rendered ineffective manually, through the controller for the element.

Another object of the invention is to provide a circuit controller in which the movable contact is biased to either its open or closed position, for example, by a spring, which contact can be moved at will from its closed position to open position. And, in furtherance of this object, it is still another object to utilize an electromagnet, which is intermittently energized, for moving the contact from its open to its closed position.

Further objects and advantages of the present invention will be apparent from the following description, reference being had to the accompanying drawings wherein a preferred form of embodiment of the invention is clearly shown.

In the drawings:

Fig. 1 is a diagrammatic view of one form of the control system applied to a heat exchange device, the device shown being a mechanical refrigerator; and

Fig. 2 is a view of one of the controllers shown in Fig. 1, but showing same with the armature in a different position and showing parts thereof in cross section.

Referring to the drawings, an electrically operated signal 20 in the form of a bell is connected in a signal circuit which is energized by a source

2

of current, herein shown as a battery 21. The signal circuit includes battery 21, wire 22, movable contact 23, either of contacts 25 or 26, wire 27, stationary and movable contacts 28 and 29, post 30, wire 31, signal 20 and wire 32.

Movable contact 29 forms a part of a controller 35. This controller 35 includes a base 36 which carries the post 30. A V notch 37 (see Fig. 2) in the post forms a socket type pivot for a lever 38; this lever is formed of metal and includes spaced branches 40, one being disposed at the front and the other at the back of the post. An end yoke 41 connecting the branches 40 rests for pivotal movement in the V notch 37. The branches 40 merge at 42 on the side of the post opposite the V notch 37. Contact 29 is carried by the lever 38. Alternate upwardly and downwardly extending projections 44 and 45 are formed on the lever 38 adjacent the merging portion 42 to form a pivotal socket 46 for one end 47 of a leaf spring 48. The other end 49 of the leaf spring is disposed in a V notch 50 in post 30. The positions of the notches 37 and 50 and socket 46 are such as to bias the lever either in a contact closing position, as shown in Fig. 1, or in a contact open position, as shown in Fig. 2, i. e. the leaf spring may buckle in either direction and the lever will be resiliently maintained in either position to which it is moved. The stationary contact 28 limits the downward movement of lever 38 and a suitable stop 52 limits the upward movement of the lever.

An electromagnet 54 is carried on the top side of base 36 below the lever 38 and an armature 55 is carried by the lever 38 in cooperative relation with the magnet 54. If the lever 38 is in its open circuit position, as shown in Fig. 2, the armature 55 will be attracted when the electromagnet 54 is energized. This will cause the lever 38 to be snapped from its open circuit position to its closed circuit position. The leaf spring 48 then functions to yieldingly hold the lever 38 in its closed circuit position.

The lever 38 can be moved manually from position shown in Fig. 1 to the position shown in Fig. 2 by a push rod 57. Rod 57 extends through and is guided by the base 36 and a bracket 58 carried by the base. A collar 59 is fastened to the rod 57 above the base 36 which collar is adapted to abut the top side of the base to limit the downward movement of the rod. A coil spring 60 surrounds rod 57 and is interposed between the collar 59 and bracket 58 for returning the rod to its retracted position. The rod 57 can be moved upwardly, manually, a sufficient distance to effect

reverse buckling of leaf spring 48 so that the lever 38 will be biased by the spring 48 to its open circuit position.

The electromagnet 54 is intermittently energized and deenergized and is herein shown as being energized concurrently with a current consuming element of the device which is to be controlled. The element is herein shown as an electric motor 62 of the type having a starting winding 63 and a running winding 64. The starting winding 63 of the motor 62 is interrupted by a motor starting relay 66. The relay 66 may be of the type shown in the patent to E. C. Raney No. 2,304,018, issued December 1, 1942. The relay 66 includes a base 67 formed of dielectric material. A metal bracket 68 is suitably secured at one end thereof to the base 67, and one end thereof is connected to a terminal 69. A bimetallic strip 71 has one end thereof 72 secured to the underside of bracket 68. The other end of strip 71 carries a contact 74. Contact 74 is arranged to engage a contact 75 which is carried by the free end of a second bimetallic strip 76. The other end of strip 76 is anchored to a post 78. Contact 75 is connected by a resilient conductor 79 to a terminal 80. Metallic post 78 is connected by a heating coil 81 to a terminal post 82.

Starting winding 63 is connected by a wire 84 to a condenser 85 which, in turn, is connected to terminal 69 by wire 86. The running winding 64 of the motor is connected by a wire 87 to the terminal 82. Terminal 80 is connected to one of the mains 89 by a wire 90. The circuit to the running winding of the motor is traced as follows: main 89, wire 90, terminal 80, conductor 79, contact 75, bimetallic strip 76, post 78, heating coil 81, terminal 82, wire 87, motor winding 64, wire 91, stationary contact 92, movable contact 93, stationary contact 94, wire 95 and the other main 96. The circuit for the starting winding 63 is traced from the terminal 80 as follows: Conductor 79, contacts 75 and 74, bimetallic strip 71, bracket 68, terminal 69, wire 86, condenser 85, wire 84, winding 63 to wire 91 which, as previously explained, is connected to the main 96. The starting winding will remain in circuit until the motor has attained its normal running speed. The bimetallic strip 76 is proportioned so that the initial heavy flow of current through the circuit will heat the bimetal and cause the same to deflect downwardly and open the starting winding circuit switch contacts 74 and 75. This opening is effected in a short time equivalent to the time necessarily required for the motor to attain running speed. The flow of current through the strip 76, during normal running of the motor, will not heat the strip sufficiently to maintain the starting switch open during the running of the motor. The heater 81, however, is proportioned so that it is heated sufficiently by the flow of current through the motor, during normal operation thereof, to heat the strip 76 for maintaining the starting switch open.

The electromagnetic coil 54 is connected in parallel with the starting winding 63 of the motor 62 by wires 98 and 99, wire 98 being connected to wire 86 and wire 99 being connected to wire 91. Thus, it will be seen that when the motor is started, electromagnetic coil will be energized, and, the circuit thereto will be interrupted simultaneously with the interruption of the starting winding circuit. As previously stated, if the switch is in the position shown in Fig. 2, it will be moved to the position shown in Fig. 1 when the motor 62 is started.

The heat exchange device is illustrated as a mechanical refrigerator in which the compressor 101 thereof is driven by a pulley 102 and this pulley is driven by a motor pulley 103 and a belt 104. The evaporator 106 of the refrigerator is disposed in the storage compartment 107 of an insulated cabinet 108. The outlet end of the evaporator 106 is connected to the low pressure side of the compressor 101 by a pipe 110. The high pressure side of the compressor 101 is connected to the condenser 111 which, in turn, is connected by a pipe 112 to a pressure reducing element 113 and this element 113 in turn is connected by a pipe 114 to the evaporator. When the compressor 101 is in operation, gaseous refrigerant is withdrawn from the evaporator 106 through the pipe 110. The compressed refrigerant is forced into the condenser 111 where it is liquefied and the liquid refrigerant is then conducted to the evaporator through the pressure reducing element 113.

In order to maintain the desired temperature in the compartment 107, the refrigerator is operated intermittently, that is, the refrigerator compressor is stopped when the temperature of the compartment attains a predetermined low value and is restarted when the compartment attains a predetermined high temperature. In order to accomplish this, there is provided a controller 116 which includes the contacts 92, 93 and 94. The controller is actuated by the expansion and contraction of volatile fluid contained in a thermostatic system. The system includes the tube 117 having one end 118 thereof terminating within the compartment 107. The other end of the tube is connected with the interior of a contractable and expansible cell 119. When the temperature of the compartment increases, the pressure within the thermostatic system increases causing the expansion of cell 119, and when the temperature of the compartment is decreased, the pressure in the thermostatic system decreases causing a contraction of the cell 119.

The controller includes a lever 121 which is pivotally mounted at 122. The bottom side of one arm 123 of the lever 121 is engaged by a pivot 124 mounted on the cell 119. A coil spring 126 bears downwardly upon the top side of the arm 123 and holds the arm 123 upon the pivot 124. The tension of spring 126 can be varied by a screw 127 threaded in a stationary part 128 of the controller 116. The other arm 130 of controller 116 carries a downwardly projecting pivot 131. A downwardly extending lever 132 is pivotally mounted on the pivot 131 and carries the movable contact 93. One end of coil spring 133 is connected to the lever 132 and the other end is connected to the arm 130 of the lever 121. The connections of the ends of the spring 133 with the lever 132 and the arm 130 and the position of the pivotal point of the lever 132, are such that the spring tends to resiliently hold the lever 132 in the switch opening position or switch closing position, depending upon the position of the lever 121. The contacts 92 and 94 form one of the stops for the lever 132 and another stop is provided and indicated at 135.

From the foregoing, it will be seen when the temperature of the compartment attains a predetermined high value, the cell 119 will expand sufficiently to cause the lever 132 to be moved with a snap action from its open contact position to its closed contact position to start the motor 62 and when the temperature of the compartment 107 attains a predetermined low value, the con-

tact 23 will be open with a snap action to interrupt the motor circuit.

Heat exchange devices are usually used by the inexperienced, and quite often, the devices are overloaded. In the case of the refrigerating system, the user may be careless, permitting the door to the compartment to be open for too long intervals or too much warm food may be placed in the compartment. These are often the conditions in grocery stores and butcher shops. It is desirable to warn the user of the overloaded condition imposed on the refrigerator. To accomplish this, the extended end of the arm 130 of the lever 121 of controller 116 is arranged to engage the movable contact 23. In the event the compartment 107 attains a predetermined high value above that normally desired, the cell 119 will have expanded sufficiently to cause the lever 130 to move contact 23 into engagement with contact 26. This will complete the signal circuit, previously described. The operation of the signal may be objectionable and to overcome this objection, the signal circuit can be broken, through the push rod 57, by separating contact 29 from contact 28. The lever 38 will be retained in the circuit opening position by the buckled spring 48 until the next succeeding starting operation of the motor, at which time, the electromagnetic coil will be reenergized to again close contact 28 with contact 29 so that the signal circuit will be reconditioned for operation for the next succeeding abnormal condition.

Another abnormal condition that may occur is the leakage of thermostatic fluid from the thermostatic system, as for example, by the cracking of the flexible material of the cell 119. When this occurs, little or no resistance will be offered to the spring 126 with the result that the lever 121 will be moved in a counterclockwise direction sufficiently to cause the movable contact 23 to engage contact 25 to complete the signal circuit at this point.

From the foregoing, it will be seen that in addition to providing a signal for the failure of the controller 116, the control system conditions the signal circuit for each cycle of operation so that the user is rewarned of an abnormal overload condition if he has manually disconnected the signal circuit.

While the form of embodiment of the present invention as herein disclosed constitutes a preferred form, it is to be understood that other forms might be adopted, all coming within the scope of the claims which follow:

I claim:

1. In a control system for a heat exchange device of the character described including a storage compartment and power operated means for circulating a fluid refrigerant to provide for cooling the compartment, in combination, a main circuit supplying power to said power operated means, a main switch in said circuit for controlling the flow of power therein, an electrically responsive means energized when said switch is closed, a signal circuit including a switch actuated by said means, said signal circuit including a third switch, means operable in response to temperature changes at the upper and lower limits of a predetermined temperature range within the storage compartment to actuate the main switch, and said means also operably constructed to respond to temperature changes above and below the upper and lower limits respectively of said predetermined temperature range and close the sig-

nal circuit through said third switch in response thereto.

2. In a control system for a heat exchange device of the character described including a storage compartment and power operated means for circulating a fluid refrigerant to provide for cooling the compartment, in combination, a main circuit supplying power to said power operated means, a main switch in said circuit for controlling the flow of power therein, an electrically responsive means energized when said switch is closed, a signal circuit including a switch actuated by said means, said signal circuit including a second switch means, means operable to actuate the main switch in response to temperature changes at the upper and lower limits of a predetermined temperature range within the storage compartment, and said means also operably constructed to respond to either temperature changes above or below the upper and lower limits respectively of said predetermined temperature range and to a failure of said temperature responsive means, to close the signal circuit through said second switch means.

3. In a control system for a heat exchange device of the character described including a storage compartment and power operated means for circulating a fluid refrigerant to provide for cooling the compartment, in combination, a signal circuit including a switch, means for biasing said switch either to an open or a closed position, electrical means for moving the switch from open position to closed position, said signal circuit including a second normally open switch means, a main switch supplying power to said power operated means, and means operable to actuate the main switch in response to temperature changes at the upper and lower limits of a predetermined temperature range within the storage compartment, and said means also operably constructed to respond to either an overload condition in said storage compartment wherein a temperature condition above said predetermined temperature range occurs or when a failure of said temperature responsive means occurs to close said second switch in the signal circuit.

4. In a control system for a heat exchange device of the character described including a storage compartment, power operated means for circulating a fluid refrigerant to provide for cooling the compartment, and employing an electrical current consuming element and an electrical circuit therefor to supply electric power to said power means, in combination, a main switch for said circuit controlling the flow of current therein, a second switch, means for biasing the second switch either to an open or to a closed position, electrical means energized when the main switch is closed for moving said second switch from the open to the closed position, means for moving the second switch to the open position, said biasing means being capable of holding the second switch in open position while the current flow is normal in the circuit for the current consuming element, a signal circuit including the second switch, and means having a pressure responsive element operable to actuate the main switch in response to temperature changes at the upper and lower limits of a predetermined temperature range within the storage compartment, said operable means also constructed to respond to both temperature changes above and below the upper and lower limits respectively of said predetermined temperature range and to a failure of said pressure responsive element to operate properly

to close the signal circuit if the second switch is closed.

5. In a control system, a heat exchange device, a current consuming element for changing the temperature of the heat exchange device, a main circuit including the current consuming element, a main switch in said circuit, an electrically responsive means energized when said switch is closed, a signal circuit including a switch actuated by the electrically responsive means, a second switch in the signal circuit, means for controlling the opening and closing of the main switch to maintain the heat exchange device normally between predetermined high and low temperature limits, said last means including a thermostatic means responsive to the temperature of the heat exchange device and connected with the main switch for actuating the same, said thermostatic means including mechanism for actuating the second switch in the signal circuit when the temperature of the heat exchange device is abnormal to one of its normal temperature limits.

6. In a control system, a heat exchange device, a current consuming element for changing the temperature of the heat exchange device, a main circuit including the current consuming element, a main switch in said circuit, an electrically responsive means energized when said switch is closed, a signal circuit including a switch actuated by the electrically responsive means, a second switch in the signal circuit, means for controlling the opening and closing of the main switch to maintain the heat exchange device normally between predetermined high and low temperature limits, said last means including a thermostatic

means responsive to the temperature of the heat exchange device and connected with the main switch for actuating the same, said thermostatic means including mechanism for actuating the second switch in the signal circuit when the temperature of the heat exchange device is abnormal to one of its normal temperature limits, means operable after the main circuit is closed for rendering the electrically responsive means ineffective to close the first mentioned switch in the signal circuit after said first mentioned switch is opened, and manual means for opening the first mentioned switch.
